(57) **CLAIM**

The ornamental design for double ended resilient microelectronic connector, as shown and described.

DESCRIPTION

The double ended resilient microelectronic connector is used for making electrical and mechanical connection between mating ball terminals as shown in broken lines proximal to the top and bottom of the connector in FIG. 7.

FIG. 1 is a perspective view of a double ended resilient microelectronic connector showing my new design;

FIG. 2 is a front elevational view thereof, the rear elevational view being identical to the front elevational view;

FIG. 3 is a left side elevational view thereof;

FIG. 4 is a right side elevational view thereof;

FIG. 5 is a bottom view thereof;

FIG. 6 is a top plan view thereof; and,

FIG. 7 is a rear elevational view thereof, showing a typical usage configuration.

The broken line portion of FIG. 7 is included to show unclaimed mating ball terminals only and forms no part of the claimed design.
